UNITED STATES PATENT OFFICE.

ALBERT B. GIETT AND RENNE W. KNOWLES, OF CLEVELAND, OHIO, ASSIGNORS TO THE WHITE COMPANY, OF CLEVELAND, OHIO, A CORPORATION OF OHIO.

SECTIONAL STAND.

Application filed October 1, 1925. Serial No. 59,919.

This invention relates to sectional stands, and relates particularly to that type of sectional stands which are adaptable to the purpose of displaying pictures and advertising signs and which are especially useful as applied to picture exhibition stands or supports adapted to be knocked down and conveniently packed for shipment.

One object of the invention is to provide a sectional stand having a plurality of detachably connected walls in which light weight and great strength are combined.

Another object of the invention is to provide a section stand the sections of which may be readily disunited and stored in a flat compact crate or container for shipment.

Another object of the invention is to provide an improved illuminated display stand for exhibiting a number of pictures or signs which are made of a translucent material.

Other objects of our invention and the invention itself will be disclosed in the following description of an embodiment of our invention and in which description reference will be had to the accompanying drawings forming part of this specification.

In the accompanying drawings,

Figure 1 is a side view of an improved display stand, embodying our invention.

Figure 2 is a vertical section taken through one of the sides adjacent the center.

Figure 3 is a detail view in section taken through the upper portion of the picture supporting frame, upon a plane indicated by the line 3-3 in Figure 1.

Figure 4 is a similar view taken through the lower portion of the frame, the section being indicated by line 4-4 in Figure 1.

Figure 5 is a horizontal section taken on the line 5-5 of Figure 2.

Figure 6 is a perspective of a portion of the display stand corner locking bar.

Figure 7 is a detail view in section taken through the side members of the picture supporting frame upon a plane indicated by the lines 7-7 in Figure 1.

Figure 8 is a detail view in elevation of the lower portion of the picture supporting frame.

Referring to the drawing, in which like parts are designated by like reference characters, the four-sided closed display stand comprises three superimposed sections 10, 11 and 12, and a cap 13. Each section is composed of four separable plates or panels, designed

with flanged top and bottom edges to accommodate the telescopic engagement of the contiguous sections. As shown in Figures 1 and 2, the plates forming the base section 10, and the upper section 12, of lesser rectilinear perimeter are vertically disposed, while plates of the intermediate section are inclined inwardly to connect the upper edge of the base section with lower edge of the upper section.

We preferably construct our improved display stand of sheet metal of a gauge suitably light for the purpose, and we thus secure a device which is relatively light. At the same time ample strength and durability is attained by the manner of forming and connecting the various units.

The bottom of each panel of the base 10 is formed with an inwardly depending flange 14, and the upper edge of the panel is constructed with a inwardly and downwardly depending flange 15.

The side edges 16 converge inwardly and rearwardly forming channels or grooves 17 adapted to engage the flanges 18 of a locking bar 19 as shown in Figure 5. The grooves 17 are of a proper width to permit a free sliding movement of the locking bar 19, when the panels are attached and a handle 20, secured to the locking bar, further accommodates the ease of assembly. Additional locking and strengthening members are provided by securing hooks 21, near one edge of each panel and co-operatively positioning eyelets 22, on the adjacent panel.

As shown in Figures 1 and 2, there are pockets or racks 23, rigidly secured to the outer face of each of the panels of the base 10. The pockets are provided to retain and display pamphlets and the like and are preferably constructed of channel irons, the outer flanges of which are of a suitable width to support the pamphlets without obscuring their cover.

The section 11, which is superjacent the base 10, is, in the present case, in the form of a pyramidal frustum and is of a design similar to the base being constructed of separable panels provided with corner locks 19, and hooks 21. The lower edges of the panels 11, are formed with inward and downward depending flanges 24 adapted to permit the base 10, to be nested in the upper section 11, and flanges 25, are provided on the upper edge of the panels 11, to pilot and support the section 110

12. The panels in sections 11 and 12 are constructed with apertures 26, into which frames 27, for retaining the subject matter to be displayed, are detachably secured.

5 We preferably construct the frames 27, of sheet metal which is formed with upper and lower marginal grooves 28, of like construction. These grooves are of a suitable width to retain the edges of a picture 29, a mat 30, and 10 a pane of glass 31. As shown in Figures 1, 3, 4 and 8, the frame comprises two members 27^a and 27^b, joined by upper and lower channel-shaped bars 32, of identical construction, 15 yieldingly secured in grooves 28, by upper and lower flanges 33, rolled inward and upward, and inward and downward, respectively, so as to envelop the outer flanges of the 20 guide bars 32. The frames 27 are attached to the panels of the sections 11 and 12, by inserting a grooved ledge 34, formed in the rear wall of the frame, through the apertures 26, and elevating the frame until a ledge or hook, 25 35, depending rearwardly from the frame, may be admitted into the opening 26, and brought into engagement with the edge of the aperture in the panel. Lateral alignment of the frames is afforded by flanges 36, which 30 depend rearwardly from the rear walls of the frame members 27^a and 27^b, and extend through the apertures 26 abutting the vertical 35 edges of the opening as shown in Figure 7.

The assembly of the frame is effectuated by 40 separating the frame members 27^a and 27^b sliding the picture, mat and glass into the 45 grooves 28, in one of the members, inserting the guide bars 32 into the other frame member, and sliding the two sections 27^a and 27^b together.

The frame as above described has generally 40 a vertical medial cross sectional form similar to the letter U and an inverted letter U except that the forward flanges are of much greater length than the rear or inner flanges. The border portions of the supporting wall 45 are encompassed between these flanges and the bases of the U section are in juxtaposition with the upper and lower edges of the opening in the supporting wall.

The embodiment of our invention herein

illustrated and described is preferably provided with an electrical fixture 37, comprising an electric lamp 39, which may be used to illuminate the pictures or signs mounted in the frames 27, and we preferably provide the cap 13, with a cover plate 38, coated with a reflective material that will increase the brilliancy of the illumination.

When it is desired to disassemble the sectional stand the sections 10, 11, 12 and 13 may be lifted apart and the panels comprising these sections may be readily disunited by releasing the hooks 21, and withdrawing the locking bars 19. The cap, panels and the associated elements thereof, are substantially flat pieces when disunited, and by virtue of this design the knocked down stand may be conveniently packed in a relatively small crate or box where it is necessary to ship the display stand or to move it about.

We wish it understood that we do not limit our invention to the specific forms of construction which have been shown and described, except as indicated in the claims which follow.

We claim:

1. In a display fixture, in combination with an apertured supporting wall, a removable display frame comprising inset rearwardly extending fastening means insertable through said aperture, said means having oppositely disposed grooves formed therein adapted to receive portions of the wall surrounding the aperture, one of said grooves being deeper than the other.

2. In a display fixture, in combination with an apertured supporting wall, a removable display frame comprising two inset rearwardly and oppositely disposed outwardly curved flanges insertable through said aperture, the troughs formed by said flanges receiving portions of the wall surrounding the aperture, one of said troughs being deeper than the other.

In testimony whereof we hereunto affix our signatures this 17th day of September, 1925.

ALBERT B. GIETT.
RENNE W. KNOWLES.
